AUTOMOBILE HEATER

Thomas F. Spackman, Chicago, Ill., assignor to
Stewart-Warner Corporation, Chicago, Ill., a
corporation of Virginia

Application December 23, 1939, Serial No. 310,711

3 Claims. (Cl. 257—124)

My invention relates generally to automobile heaters, and more particularly to an improved heat exchanger for heaters of this type.

It is an object of the invention to provide an improved heat exchange device comprising essentially a single die cast element having a number of circuitous passageways extending therethrough.

A further object is to provide an improved heat exchanger for automobile heaters of the internal combustion type in which the core consists of a unitary die casting having generally parallel interconnected passageways extending therethrough.

A further object is to provide an improved heat exchange device for automobile heaters which is simple in construction, may be economically manufactured, and which is efficient in operation.

Other objects will appear from the following description, reference being had to the accompanying drawings, in which:

Figure 1 is a fragmentary vertical sectional view of an automobile heater of the internal combustion type showing the improved heat exchange device;

Figure 2 is a transverse vertical sectional view taken on the line 2—2 of Fig. 1;

Figures 3 and 4 are similar sectional views taken on the lines 3—3 and 4—4 respectively of Fig. 1;

Figure 5 is a fragmentary sectional view taken on the line 5—5 of Fig. 2; and

Figure 6 is a developed sectional view taken on the circular line 6—6 of Fig. 4, and diagrammatically illustrating the manner in which the gases of combustion flow through the passageways.

Referring to Fig. 1, the heater in which the heat exchange device of my invention may be used advantageously comprises a combustion chamber casting 10 having a combustion chamber 12, to which a mixture of fuel and air provided by a carbureting device 14 is supplied through a tube 16, the tube 16 having a side-wardly facing opening 18 adjacent a baffle 20 which partially obstructs the flow of the combustible mixture to the combustion chamber 12. Fuel is supplied to the carbureting device 14 from a suitable reservoir 22, which may be the float bowl of the engine carburetor of the automobile upon which the heater is mounted, or which may be a separate auxiliary fuel reservoir. The mixture supplied by the carbureting device 14 is drawn into the combustion chamber due

to suction of the intake manifold of the engine, the casting 10 having an outlet passageway 24 which communicates through a conduit 26 with the intake manifold 28. A compensator 30 having a Venturi-shaped passageway extending therethrough is adapted to be closed by a valve 32 formed at the end of the valve stem 34 which has an operating button 36 secured at the outer end thereof. The gases of combustion, when the valve 32 is open, flow from the combustion chamber 12 through ports in a reigniter 38 and openings in a baffle 40 to the passageways in a heat exchanger casting 42. After passing through the circuitous passageways in this casting 42, the gases flow through the compensator 30, and hence to the intake manifold of the engine. Air from the passenger compartment of the vehicle is forced downwardly over the heat exchange device by a fan 44 driven by a motor 46. Suitable electrical circuits controlled by a switch mechanism 48 are provided so that upon pulling the button 36 to open the valve 32, an igniter 50 of the resistance wire type is connected in circuit so as to be heated to incandescence, and thus ignite the combustible mixture in the chamber 12. The switch mechanism 48 also includes a thermostatically controlled switch which connects the motor 46 to the source of power after the heat exchange device has attained a predetermined temperature, and also disconnects the igniter 50 from the source of current, usually the storage battery of the automobile.

The heater, as thus far generally described, is disclosed in greater detail in the co-pending application of Henry J. DeN. McCollum, Serial No. 120,523, filed January 14, 1937, which has matured into Patent No. 2,191,174 dated February 20, 1940.

Referring now more particularly to the novel heat exchanger, the casting 42 is generally cylindrical in shape having an end flange 52, the outer face of which abuts against the end of the combustion chamber casting 10, the flanged end having an annular recess 54 to receive a complementary projection 56 formed upon the casting 10. The baffle 40 is held in place between the end of the projection 56 of the casting 10 and a shoulder 58 formed at the end of the recess 54. As shown in Fig. 3, the baffle 40 has a relatively large opening 60 formed therein in communication with a passageway 62 formed in the casting 42 and extending the full length thereof. The rearward (left-hand) end of the walls of the passageway 62 are provided with openings 62a connecting the passageway 62 with passageways 63 and 64 respectively. The forward ends of the

passageways 63 and 64 communicate with passageways 65 and 66 respectively through ports 68, while the rearward ends of the passageways 65 and 66 communicate with passageways 69 and 70 respectively through ports 72. The forward ends of the passageways 69 and 70 communicate with the passageway through the compensator 30 via ports 73 and 74. From the foregoing, it will appear that gases of combustion flowing through the opening 60 in the baffle plate 40 flow rearwardly through the passageway 62 and then divide, one part flowing to the compensator 30 through passageways 63, 65, and 69, while the other part flows to said compensator through passageways 64, 66, and 70.

In order to prevent so-called "motor boating," the baffle 40 is provided with a pair of openings 75 and 76 which permit a small quantity of the gases of combustion to flow into the passageways 65 and 66 respectively. The admission of this small quantity of gas to these passageways effectively counteracts a tendency, which might otherwise be present, for the gas to expand and contract in an oscillatory manner. Such expansion and contraction of the gases flowing through the passageways causes an annoying noise, aptly described as "motor boating" due to its similarity with the noise of a motor boat exhaust.

The external cylindrical surface of the heat exchange casting 42 is provided with a longitudinal groove 78. A plurality of heat conducting fins 80 are pressed over the casting 42, each of these fins having a cylindrical flange 82 engaging the casting forming a means for spacing the fins. These flanges 82 are in snug engagement with the outer wall of the casting 42 so as to form efficient parts for heat conduction from the casting to the fins. Each of the flanges 82 has a dent 84 formed therein for cooperation with the groove 78 in the casting 42. The fins are thus locked against rotation with respect to the casting.

The manufacture of the die casting 42 with its numerous interconnecting passageways is accomplished in an ingenious manner. Due to the limitations in the die casting operation, it is not feasible to form the openings 62a and 72 which connect the rearward ends of the various passageways by die core parts which are withdrawn from the forward end of the casting. To obviate this difficulty, the die casting die is provided with four pins conformed to interengage with the portions of the die used for forming the passageways 62 to 66, 69, 70, to form the openings 62a, 72, to the shape best illustrated in Fig. 5. The withdrawal of the four pins for forming the opening 72 results in leaving four cylindrical openings 86 in internal bosses 88. These openings are closed by means of cylindrical plugs 90, the ends of which are chamfered and which are secured in position to seal cylindrical openings by swaging or peening material from the casting 42 over the outer chamfered ends of the plugs, as indicated in Fig. 5.

The rearward end of the casting 42 has a projection 92 engaging in a complementary hole formed in a mounting plate 94 carrying the switch mechanism 48, the mounting plate being secured to the casting 42 by a bushing 96 threaded in the casting and also forming a guide for the valve stem 34.

The casting 42 is preferably made of an aluminum alloy containing in the order of 95% aluminum and 5% silicon, the plugs 90 being

made of the same alloy so as to have the same coefficient of expansion and contraction, or they may, if desired, be made of cold rolled steel, providing they are carefully swaged in place. While leakage past the plugs is undesirable, and can readily be prevented, such leakage would not seriously interfere with the operation or safety of the heater, since the passageways in the casting 42 are, whenever the heater is in operation, at subatmospheric pressure, and therefore any leakage would be of atmospheric air into the passageways rather than leakage of gases of combustion to the atmosphere. The plugs 90 are, however, of such size that they have to be pressed into the bores 86 formed in the bosses 88, such press fit usually assuring that there will be no leakage past the plugs and that the plugs will remain in place. The swaging operation is thus an added precaution to assure that the plugs will not become loose or permit leaking of air into the passageways of the casting.

From the foregoing description, it will appear that relatively long passageways for the gases of combustion are provided in the casting 42 so that the transfer of heat from the gases to the casting is very efficient. The casting being mainly of aluminum, it is a good conductor of heat and is in good heat conducting relationship with the fins 80, which are preferably of copper. Thus, within a relatively small space, a large amount of heat may be transferred from the gases of combustion to the air forced downwardly past the heat radiating fins by the motor driven fan 44.

Since the body of the heat exchange device is essentially a unitary casting, and since the insertion of the plugs 90 is a relatively simple operation, it will be apparent that the body may be very economically produced. Similarly, the assembly of the fins 80 on the casting 42 is a very simple operation, since these fins need merely be pressed over the casting one after another. The partitions between the various passageways 63 and 65, 69, and 70, are of sufficient thickness to provide adequate metal for conduction of heat from the gases flowing through the passageways to the external cylindrical wall of the casting and thence to the heat radiating fins 80. The casting 42 is of such construction that it may be readily cast without the possibility of having a large proportion of defective castings. Furthermore, the casting is of a rigid and structurally strong shape for the amount of metal used, contributing to its durability and utilization as a structural part of the heater.

While I have shown and described a particular form of my invention, it will be apparent to those skilled in the art that numerous modifications and variations may be made without departing from the underlying principles of the invention. I therefore desire, by the following claims, to include within the scope of my invention all such similar and modified constructions whereby substantially the results of the invention may be obtained by substantially the same or equivalent means.

I claim:

1. A heat exchange device comprising a unitary casting having a plurality of interconnected longitudinally extending passageways therein, said passageways opening toward one end only of said casting, said casting having a shoulder formed at the end thereof at which said passageways are open, and a baffle plate pressed against said

shoulder, said baffle plate covering the ends of said passageways and having an opening for admitting a heating medium to at least one of said passageways.

2. A heat exchange device comprising a unitary casting having a plurality of spaced walls forming interconnected longitudinally extending passageways therein, said passageways opening toward one end only of said casting, said casting having a shoulder formed adjacent the open ends of said passageways, a baffle plate pressed against said shoulder, said baffle plate covering the ends of said passageways, some of the walls of said passageways having core holes extending from the closed ends of adjacent passageways longitudinally of and intersecting the walls, thereby

10 forming ports connecting said passageways, and a plurality of plugs secured in said casting to close the open ends of said core holes.

3. A die cast heat exchanger comprising a unitary casting having a plurality of generally parallel passageways formed therein and separated by partitions, some of said passageways being closed at one end of said casting, some of said partitions having holes extending a short distance from the closed end of said passageways longitudinally of and intersecting said partitions, thereby forming ports connecting said passageways, and a plurality of plugs secured in said casting to close the open ends of said holes.
